WALL RANGE

William S. Davis, Knoxville, Tenn.

Application December 18, 1935, Serial No. 55,105

3 Claims. (Cl. 219—37)

The present invention relates to new and useful improvements in electric ranges or stoves and has for its primary object to provide, in a manner as hereinafter set forth, a device of this character which, when not in use, may be conveniently swung to an out-of-the-way position in a wall.

Other objects of the invention are to provide a wall range of the character described which will be simple in construction, strong, durable, highly efficient and reliable in use, compact, attractive in appearance and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a wall range constructed in accordance with the present invention.

Figure 2 is a top plan view, showing the invention in open or operative position.

Figure 3 is a vertical sectional view, taken substantially on the line 3—3 of Figure 2.

Figure 4 is a vertical sectional view, taken substantially on the line 4—4 of Figure 1.

Figure 5 is a horizontal sectional view, showing the automatic main control switch.

Referring now to the drawings in detail, it will be seen that the embodiment of the invention which has been illustrated comprises a cabinet 1 of suitable material, preferably stainless steel, which is mounted in a chamber 2 which is provided therefor in a wall 3 which may, of course, also be of any suitable material. The cabinet 1 is open at its front and said cabinet is surrounded by an angle iron frame 4 which is also fixed in the wall 3.

Hingedly mounted, as at 5, on the bottom of the cabinet 1 is a closure 6 of suitable metal from the sides and top of which a flange 7 projects. As illustrated to advantage in Figure 4, the closure 6, when in closed position, is adapted to project into the cabinet 1 and the flange 7 is adapted to abut the front of said cabinet and the frame 4. Countersunk in the front of the closure 6 is a panel 8 of suitable material.

The closure 6 is substantially filled with a suitable heat insulating material 9 over which a cover plate 10 is provided. Electric heating units 11 are mounted on the inner side of the closure 6. Also mounted on the hingedly mounted clo-

sure 6 are electric switches 12 for the units 11. The reference numeral 13 designates a suitable latch for releasably securing the closure 6 in closed position, as also shown to advantage in Figure 4 of the drawings.

Referring now to Figure 5 of the drawings, it will be seen that a main control switch 14 is mounted on the frame 4 in the wall 3 adjacent the cabinet 1, said switch 14 including a plunger 15 extending slidably through an opening which is provided therefor in the said frame 4. Of course, the switch 14 is interposed in the electric circuit to the units 11. The reference numeral 16 designates conductor wires to the units 11.

When the range is not in use, the closure 6 is swung upwardly into the cabinet 1 as seen in Figure 4 of the drawings. When in this position, the flange 7 engages and forces the plunger 15 inwardly for opening the switch 14 thereby automatically deenergizing the units 11 in the event that either of the switches 12 should be left closed unintentionally. When the range is to be used the latch 13 is, of course, disengaged to permit the closure 6, with the units 11 thereon, to be swung downwardly to a substantially horizontal position, as seen in Figure 3 of the drawings. When this operation takes place the switch 14 automatically closes. Then, either or both of the units 11 may be energized as desired through the medium of the switches 12. Lugs 17 are provided on the hinged end of the closure 6 for engagement with the frame 4 for supporting said closure 6 in a horizontal position. If desired, the device may be mounted in a cabinet, under a bar or any other desirable place. Also, if desired, the latch for the closure 6 may be electrically operated.

It is believed that the many advantages of a wall range constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A wall range including an open front cabinet mounted in the wall, a frame imbedded in the wall and surrounding the front edge of the cabinet, a cooking unit hingedly mounted at the lower edge of the cabinet to close the latter and comprising a closed casing filled with insulating material and adapted in the closing position of the unit to project into said cabinet, and elec-

tric heating unit countersunk in the top of said casing and into said material, a plunger type switch mounted in said wall behind the top of said frame and having an inwardly movable plunger normally extending through the latter, a flange on said casing engaging said plunger in the closing position of said container to move said plunger inwardly, and a flexible cable connection between the switch and unit extending from said switch to said wall and cabinet and into said casing and insulating material.

2. A combination of the character described comprising a cabinet, a closure for the front of said cabinet and hingedly secured thereto along one of its longer edges, a flange encircling said closure, a switch mounted in said cabinet and having a plunger projecting outwardly therefrom for breaking contact by engagement with said flange when the closure is in closed position, a

second switch positioned on the outer face of said closure and adjacent said flange, an electrical heating unit mounted on the inner face of said closure and controlled by said switches, and means for maintaining said closure in inoperative position.

3. A combination of the character described comprising a cabinet, a closure hingedly secured to the front thereof along the longer edge, a flange encircling the closure, switches mounted on the outer face of said closure adjacent said flange, electrical heating units mounted on the inner face of said closure and electrically connected with said switches, means positioned upon the hinges of the closure for limiting its movement, and additional means for normally maintaining said closure in inoperative position.

WILLIAM S. DAVIS.
